PURIFICATION OF ALKYL ARYL HYDROCARBONS

James C. Kirk, Lake Charles, La., and Edsel L. Miller, Houston, Tex., assignors to Continental Oil Company, Ponca City, Okla., a corporation of Delaware

No Drawing. Application January 8, 1958
Serial No. 707,686

10 Claims. (Cl. 260—674)

The present invention relates to the production of alkyl aryl hydrocarbons which are substantially free of color precursors. Somewhat more particularly this invention provides a method for producing such alkyl aryl hydrocarbons which, upon sulfonation and neutralization, yield a substantially color-free salt.

Sulfonation of alkyl aryl hydrocarbons has generally followed the procedure wherein about 1.3 to 2 parts by weight of 100 to 105 percent sulfuric acid or oleum is used per part by weight of the alkyl aryl hydrocarbon. Other sulfonating agents have been used but whatever agent was used, the resulting sulfonic acid when neutralized with a base such as sodium hydroxide, yields a dark-colored sulfonate. Since dark-colored sulfonates can be used only in relatively few applications, various methods have been heretofore suggested for removing such color bodies which impart color to the sulfonate. These methods have involved treating the aqueous solution of the sulfonate with bleaching agents such as peroxide or acidic reagent such as sulfuric or hydrochloric acid. Other methods have involved blowing the aqueous sulfonate solution with oxidizing gases such as free oxygen. None of these methods have been entirely satisfactory, generally because they have involved an undesirable expenditure of materials and time, and furthermore the final product so obtained has not been improved greatly in color and the resulting improvement is only transitory in nature.

It is, therefore, a principal object of this invention to provide an improved process, which process obviates the disadvantages of the prior art methods. It is another object of our invention to provide a method for the removal of color precursors from alkyl aryl hydrocarbons whereby substantially colorless sulfonates can be produced by the sulfonation of such alkyl aryl hydrocarbons followed by neutralization. Further objects and advantages of the invention will become apparent from the following description.

In its broadest aspects the invention comprises the alkylation of an aromatic hydrocarbon such as benzene or toluene with an olefin containing from 8 to 18 carbon atoms in the molecule in the presence of an alkylation catalyst under alkylation conditions. Following the alkylation reaction the resulting mixture is allowed to remain quiescent until 2 layers are formed, an organic layer and a catalyst sludge layer. The catalyst sludge is removed and then the alkyl aryl hydrocarbon recovered from the organic layer by fractional distillation. The alkyl aryl hydrocarbon is then treated with an oxidizing agent in the presence of acid and water and at a temperature varying from 20 to 100° C. for a period of time varying from 5 to 60 minutes. The oxidizing mixture is then allowed to remain quiescent for a period of time until the oxidizing materials have settled out. The oxidizing materials are withdrawn and the alkyl aryl hydrocarbon which is partially freed of color precursors is treated with about 1 to 5 weight percent of sulfuric acid based upon the weight of the alkyl aryl hydrocarbon

2

at a temperature varying from 25 to 80° C. for a period of time varying from 5 to 30 minutes. The resulting mixture is allowed to remain quiescent until the acid has settled out. By this procedure two layers are formed, the lower acid layer which contains oxidized color precursors and an upper layer which consists of the alkyl aryl hydrocarbon substantially free of color precursors. The alkyl aryl hydrocarbon is then recovered and upon subsequent sulfonation and neutralization there is obtained an alkyl aryl sulfonate which is substantially colorless.

While we do not wish to be bound by any particular theory regarding the reactions which take place during the chemical treatment of the aromatic hydrocarbon, we believe that in the preparation of alkyl aryl hydrocarbons by the reaction of an alkylating agent with an aromatic hydrocarbon in the presence of a Friedel-Crafts catalyst such as aluminum chloride, side reactions occur which lead to the formation of polynuclear aromatic hydrocarbons. These polynuclear hydrocarbons impart a blue fluorescence to the alkyl aryl hydrocarbon and are in part responsible for the dark color of the product obtained on sulfonation and neutralization of the alkyl aryl hydrocarbon. Analysis indicates that the polynuclear hydrocarbons are primarily 9-alkyl anthracenes and 9,10-di-alkyl anthracenes and may be present in the alkyl aryl hydrocarbon in concentrations up to .125 gram per liter and .075 gram per liter respectively.

Before proceeding with specific examples illustrating our invention, it may be well to indicate in general the nature and the amounts of the different materials required in the process.

The alkyl aromatic hydrocarbons which may be freed of polycyclic aromatic compounds by the process of this invention are those alkyl aromatic hydrocarbons prepared by the condensation of an aromatic hydrocarbon and an alkylating agent in the presence of a Friedel-Crafts catalyst, particularly aluminum chloride. The aromatic hydrocarbon may be benzene or a low molecular weight alkyl benzene or dialkylbenzene such as toluene, ethyl benzene, cumene, o-, m-, and p-xylene, mixtures of xylenes, naphthalene, alpha-methyl naphthalene, beta-methyl naphthalene, diphenyl, the aromatics contained in petroleum fractions, and the like. The alkylating agent may be an alkyl halide, alkanol, or olefin having from about 10 to about 20 carbon atoms. Included among the alkyl halides are 1-chlorodecane, lauryl chloride, 1-chloro-octadecane, and 1-bromodecane. Suitable alkanols are lauryl alcohol, decanol, and stearyl alcohol. Suitable olefins are decene-1, decene-2, dodecene-1, dodecene-2, pentadecenes, octadecenes, and olefins obtained by the polymerization of ethylene, propylene, isobutylene and their mixtures such as tetrapropylene, pentapropylene and hexapropylene.

The oxidizing agents suitable for use in the process of this invention are the sulfuric acid solutions of the chromates including sodium and potassium chromate and dichromate and chromium trioxide. Ozone may also be used. The preferred oxidizing agents are sulfuric acid solutions of chromium trioxide or ozone. Generally for treatment of 100 parts of the alkyl aromatic hydrocarbon an oxidizing solution containing from 0.25 to 0.75 parts of oxidizing agent, 1.5 to 5 parts of water and 2 to 6 parts of 96% sulfuric acid is effective in removing polycyclic hydrocarbons. A larger amount of oxidizing solution may be used but is unnecessary for treatment of alkyl aromatic hydrocarbons prepared as described above. The treatment consists in vigorous agitation of the hydrocarbon and the oxidizing solution at a temperature from about 20° to 100° C. for from 5 minutes to about 1 hour or longer. In general, the higher the temperature the shorter the time required to effect the purification. We

prefer to effect the purification at 60° C. for a period of 10 minutes. When ozone is used as the oxidizing agent, from about 0.3 to 0.6 grams of ozone is used per 100 parts of hydrocarbon. The ozone is passed into the hydrocarbon during a period of from about 20 to 60 minutes. Following the oxidation treatment, the treated mixture is allowed to settle and a dark-colored sludge withdrawn using, if desired, a small amount of a filtering aid to assist in coagulating the sludge. The hydrocarbon is then agitated vigorously with 1 to 5%, and preferably 2%, by weight of concentrated sulfuric acid at a temperature of from 25 to 80° C. for from 5 to 30 minutes. The sludge is then removed and the hydrocarbon treated with a basic clay such as Attapulgus clay to remove traces of acid.

Relative color density, R.C.D., is a measure of the relative amount of yellow color present in a sodium alkyl aryl sulfonate slurry. In making this test a 4% active sodium alkyl aryl sulfonate slurry is prepared and color of such a product is compared to that of a standard chromate solution which contains two milligrams of potassium dichromate per 100 cc. of a 0.05 normal potassium hydroxide solution. The color readings are made on a Klett-Summerson Photo-electric Colorimeter using a 4-centimeter cell and a Klett Color Filter No. 42. The R.C.D. is then equal to the reading of the sample divided by the reading of the standard. Obviously, the higher the R.C.D. number, the more intense the yellow color of the sodium alkyl aryl sulfonate slurry.

In order to disclose the nature of the present invention still more clearly, the following illustrative examples will be given. It is to be understood, however, that the examples given hereinafter are not intended for limiting the invention but rather to illustrate the principles and practices to be observed in producing the improvement according to my invention. Parts given are parts by weight.

Example 1

A vessel equipped with a high speed agitator was charged with 100 parts of pentadecylbenzene prepared by the condensation of pentapropylene with benzene in the presence of aluminum chloride. While agitating, 5 parts of an oxidizing solution prepared by adding 4 parts of chromium trioxide to 6 parts of water was added and the agitation continued for 20 minutes at 30° C. Two parts of Attapulgus clay was added to the agitating mixture and then the mixture was allowed to stand quiescent after which the hydrocarbon was decanted from the dark sludge. The hydrocarbon was then agitated for 15 minutes at 100° C. with 5 parts of Attapulgus clay and filtered through a Hyflo mat to yield hydrocarbon having no fluorescent bloom.

Analysis.—The initial pentadecylbenzene analyzed 0.124 g. per liter of 9-alkyl anthracenes and 0.075 g. per liter of 9,10-dialkylanthracenes. On sulfonation and neutralization a sulfonate having an R.C.D. of 2.70 was obtained.

The pentadecylbenzene treated above analyzed 0.000 g. per liter of anthracenes. On sulfonation and neutralization a sulfonate having an R.C.D. of 1.76 was obtained.

Although the use of the clay treatment gives a somewhat better product as far as color is concerned, it may be desirable to eliminate the clay treatment in many cases. This is true because of the operating difficulties involved when a clay treatment is used.

Example 2

The experiment given in Example 1 was repeated with the exception that the hydrocarbon was contacted in an additional step with 3 parts of concentrated sulfuric acid (96%) following the separation of the oxidation sludge. The sulfonate prepared from the resulting treated hydrocarbon had an R.C.D. of 1.13.

Example 3

When treated only with clay and no oxidation or sulfuric acid treatment, the hydrocarbon gave a sulfonate having an R.C.D. of 2.70.

Example 4

When treated with 3 parts of concentrated sulfuric acid and then 5 parts of clay, the hydrocarbon gave a sulfonate having an R.C.D. of 2.68.

The foregoing experiments demonstrate that it is necessary to treat the alkyl benzene prepared by the condensation of an alkylation agent with benzene in the presence of aluminum chloride with both an oxidizing solution and sulfuric acid in order to obtain a sulfonate having excellent color. Either the use of the oxidizing solution or sulfuric acid alone does not give as good a result as when both are used.

Example 5

Dodecylbenzene prepared by the alkylation of benzene with dodecene in the presence of aluminum chloride was treated as in the preceding 4 examples. The sulfonates obtained had the following colors:

From untreated dodecylbenzene	2.66
From dodecylbenzene treated with clay	2.65
From dodecylbenzene treated with oxidizing agent and clay	1.70
From dodecylbenzene treated with sulfuric acid and clay	2.58
From dodecylbenzene treated with oxidizing agent, sulfuric acid and clay	1.11

Example 6

Into 130 parts of pentadecylbenzene prepared as described in Example 1, 0.5 parts of ozone was bubbled over a period of 30 minutes at 25° C. The mixture was then agitated with 2 parts of Attapulgus clay and a dark sludge removed by decanting the hydrocarbon. The hydrocarbon was then treated at 60° C. for 20 minutes with 5 parts of sulfuric acid (96%), the sludge removed by decanting, the hydrocarbon was then contacted with 2 parts of Attapulgus clay and filtered. The product was clear, colorless and bright and had an R.C.D. of 1.70.

We have found that in those few cases where the metal salt of the alkyl aryl sulfonic acid produced by the process of this invention is still slightly colored that product may be bleached very easily by methods well known to those skilled in the art. Such bleaching methods include the treatment of the product with a bleaching agent such as a peroxide or bleaching by means of electrolysis. We have found further that if these color precursors have not been removed by the process of this invention, it is rather difficult to bleach the resulting product and the result is only transitory.

While particular embodiments of the invention have been described, it will be understood, of course, that the invention is not limited thereto since many modifications may be made, and it is, therefore, contemplated to cover by the appended claims any such modifications as fall within the true spirit and scope of the invention.

The invention having thus been described, what is claimed and desired to be secured by Letters Patent is:

1. A method of removing color precursors, of the type which adversely affect alkyl aryl sulfonates, from an alkyl aryl hydrocarbon mixture, produced in a Friedel-Crafts alkylation reaction and containing 8 to 18 carbon atoms in the alkyl group, said method comprising the treatment of said mixture with an oxidizing agent selected from the group consisting of sodium chromate, potassium chromate, sodium dichromate, potassium dichromate, chromium trioxide, and ozone in the presence of water and sulfuric acid at a temperature varying from about 20 to 100° C. and for a period varying from about

5 to 60 minutes, allowing the oxidized products to settle out thus forming two layers, an upper layer comprising the alkyl aryl hydrocarbon partially freed of color precursors and substantially freed of color precursors of the alkyl anthracene type and a lower layer comprising the oxidized products, separating the two layers, contacting said recovered upper layer with 1 to 5 weight percent sulfuric acid based on the weight of said alkyl aryl hydrocarbon at a temperature varying from about 25 to 80° C. for a period of time varying from about 5 to 30 minutes, allowing the mixture to separate into a lower layer consisting predominantly of the alkyl aryl hydrocarbon, and then separating the layers to recover thereby the alkyl aryl hydrocarbon substantially free of color precursors.

2. The method of claim 1 wherein the oxidizing agent is a chromium trioxide.
3. The method of claim 2 wherein the alkyl aryl hydrocarbon mixture comprises pentadecylbenzene.
4. The method of claim 2 wherein the alkyl aryl hydrocarbon mixture comprises dodecylbenzene. 20
5. The method of claim 1 wherein the oxidizing agent is ozone.

6. The method of claim 5 wherein the alkyl aryl hydrocarbon mixture comprises pentadecylbenzene.
7. The method of claim 1 wherein the oxidizing agent is a sodium chromate.
- 5 8. The method of claim 1 wherein the oxidizing agent is a potassium chromate.
9. The method of claim 1 wherein the oxidizing agent is a sodium dichromate.
10. The method of claim 1 wherein the oxidizing agent is a potassium dichromate.
